M. W. McCONKEY

BRAKE SHOE

Filed Feb. 16, 1927

UNITED STATES PATENT OFFICE.

MONTGOMERY W. MC CONKEY, OF CHICAGO, ILLINOIS, ASSIGNOR TO BENDIX BRAKE COMPANY, OF CHICAGO, ILLINOIS, A CORPORATION OF ILLINOIS.

BRAKE SHOE.

Application filed February 16, 1927. Serial No. 168,507.

This invention relates to brake shoes, and is illustrated as embodied in one of the end shoes of a three-shoe type of internal expanding automobile brake. An object of the invention is to form the shoe for the ready attachment of the brake lining, preferably by means of fastenings having heads seated in transverse depressions extending across the shoe and drawing the lining into the depressions.

According to one feature of the invention, the shoe has a stiffening web built up of two parts, which may be radial portions forming parts of two elements or stampings secured back to back to form the shoe, the parts having mating depressions which jointly form a radial opening through the shoe for the stem of the fastening which holds the lining. I prefer to form the end of the shoe with spaced stiffening webs (which may if desired be extended as spaced arms adapted to straddle the end of an adjacent shoe), with a separate insert secured between the webs to form a continuation of the friction face of the shoe, and with a transverse depression for the last fastening extending across the face of the insert.

The above and other objects and features of the invention, including various novel and desirable details of construction, will be apparent from the following description of one illustrative embodiment shown in the accompanying drawing, in which:

Figure 1 is a side elevation of the shoe; Figure 2 is a partial section through the end of the shoe on the line 2-2 of Figure 1;

Figure 3 is a cross section through the shoe on the line 3-3 of Figure 1; Figure 4 is a cross section through the shoe on the line 4-4 of Figure 1; and

Figure 5 is a partial inside elevation of the shoe, looking in the direction of the arrows 5-5 of Figure 1.

The illustrated shoe is intended for use as one of the end shoes of a three-shoe brake such as is fully described in Patent No. 1,567,716, granted Bendix Brake Company on December 29, 1925, on application of A. Y. Dodge. It includes generally two elements or stamped sections riveted or otherwise secured back to back, and comprising radial portions 10, preferably reinforced by short outwardly-extending flanges 12 at their inner edges, and which webs or parts

10 jointly form the stiffening web of the shoe. The friction face of the shoe is formed by cylindrical flanges 14 which are preferably integral parts of the same elements or stampings as the web portions 10. 60

In this particular shoe, in order to permit the end of the shoe to overlap the end of the adjacent shoe, webs 10 are spread apart at one end of the shoe to form spaced stiffening webs 16 which extend as spaced 65 pivot arms beyond the end of the shoe. Between these webs is welded or otherwise secured a separate insert 18, which is flush with flanges 14 so that it forms a continuation of the friction face of the shoe. At the 70 other end of the shoe there is a cam thrust plate 20 riveted to short end flanges 22 on web portions 10. At this end of the shoe, an opening 24 is provided for a post forming part of a shoe-positioning device fully 75 described in the above-identified Dodge patent and in Patent No. 1,604,394, granted Bendix Brake Company on October 26, 1926, on application of A. Y. Dodge. Openings 26 are provided in arms 16 for the anchor of an 80 adjacent shoe the end of which is straddled by those arms.

The present invention relates principally to securing to the shoe a piece of brake lining 28. Preferably flanges 14 are formed with 85 alined grooves 30, and the extensions of these flanges at the lower end of the shoe (together with the insert 18) are formed with similar alined grooves 32, to provide transverse depressions extending across the 90 shoe. The lining is drawn into these depressions by the heads 34 of T-shaped fastenings. The stems 36 of the two upper fastenings extend through radial openings entirely through the shoe and formed by 95 mating depressions pressed into the parts 10 which form the stiffening web, the radial opening for the stem 36 of the uppermost fastening being in the space between thrust plate 20 and opening 24. The stem 100 38 of the lowermost fastening extends through insert 18, between webs 16. The lining is held clamped in place by nuts 40 threaded on stems 36 and 38.

In attaching the lining, the uppermost 105 and lowermost fastenings are tightened up first, whereupon the tightening of the middle fastening serves to stretch the lining tightly upon the friction face of the shoe.

While one illustrative embodiment has 110

been described in detail, it is not my intention to limit the scope of the invention to that particular embodiment, or otherwise than by the terms of the appended claims.

6 I claim:

10 1. A brake shoe having an arcuate outer surface formed with a transverse depression, and having two stiffening parts jointly forming a stiffening web and which are provided with mating depressions jointly forming a generally radial opening intersecting the transverse depression.

15 2. A brake shoe having an arcuate outer surface formed with a transverse depression, and having two stiffening parts jointly forming a stiffening web and which are provided with mating depressions jointly forming a generally radial opening intersecting the transverse depression, in combination 20 with brake lining on the outer surface, and a fastening for the lining having a head in the transverse depression and a stem extending through the opening.

25 3. A brake shoe comprising two elements secured back to back, and including outer flanges forming an arcuate outer surface formed with a transverse depression, and having radial portions forming two stiffening parts jointly forming a stiffening web 30 and which are provided with mating depressions jointly forming a generally radial opening intersecting the transverse depression.

35 4. A brake shoe element having two portions at right angles to each other, one of which is cylindrically curved and formed with a transverse depression, and the other of which is formed with a radial depression intersecting the transverse depression.

40 5. A brake shoe having a stiffening web built up of two parts secured together, said parts being formed with mating depressions jointly forming a radial opening through the shoe.

45 6. A brake shoe comprising two elements secured back to back and having parts which jointly form a double-thickness stiffening

50 web, said parts being formed with mating depressions jointly forming a radial opening through the shoe.

7. A brake shoe having a stiffening web and a thrust plate at one end of the web, the web having an opening therethrough near the end with the thrust plate and having a radial opening entirely through the 55 shoe between the thrust plate and the first opening.

8. A brake shoe having at least adjacent one end two spaced webs integral with outwardly-extending cylindrical flanges, and a 60 separate insert secured between the webs and flush with the surfaces of the cylindrical flanges, the insert and the cylindrical flanges having alined grooves jointly forming a depression extending across the shoe: 65

9. A brake shoe having at least adjacent one end two spaced webs integral with outwardly-extending cylindrical flanges, and a 70 separate insert secured between the webs and flush with the surfaces of the cylindrical flanges, the insert and the cylindrical flanges having alined grooves jointly forming a depression extending across the shoe, the insert having an opening in the bottom of its groove for the stem of a fastening 75 having its head in the depression.

10. A brake shoe having, at least adjacent one end, a cylindrical outer surface formed with a transverse depression, and having two stiffening webs, in combination 80 with brake lining on the outer surface and a fastening having a head in the depression and a stem extending through the shoe between the stiffening webs.

11. A brake shoe comprising two elements 85 secured together, and having cylindrical flanges jointly forming the friction face of the shoe, said flanges having alined grooves which form a transverse depression extending across the friction face.

In testimony whereof, I have hereunto signed my name.

MONTGOMERY W. McCONKEY.
